UNITED STATES PATENT OFFICE.

LOUIS SEEBACH AND JOSEPH BETTSCHEN, OF GOWANSTOWN, ONTARIO,
CANADA.

MOTIVE POWER.

SPECIFICATION forming part of Letters Patent No. 281,929, dated July 24, 1883.

Application filed April 27, 1883. (No model.)

To all whom it may concern:

Be it known that we, LOUIS SEEBACH and JOSEPH BETTSCHEN, both subjects of the Queen of Great Britain, residing at the village 5 of Gowanstowm, in the county of Perth, in the Province of Ontario, Dominion of Canada, have jointly invented a certain new and useful Motive Power, of which the following is a specification.

10 The object of the invention is to devise a cheaply-constructed motive power specially adapted for driving small machinery; and it consists, essentially, of an arrangement of gearing propelled by the action of a falling 15 weight attached to a rope or chain which has been previously wound up by hand, and provided with cranks and pulleys for the purpose of directing the movement of the gearing to the machinery the motor is intended 20 to propel.

The figure is a perspective view of our improved motor, showing it as applied for the purpose of working a churn.

Although our motor may be used for propelling machinery of every description, it 25 will be sufficient for the purpose of this specification to show it as applied for working a churn.

A is the main frame of the machine. On 30 this frame we support in proper journals the shaft B, which is provided with a crank, B', connected to the lever C by the pitman D. The other end of the lever C is connected to the handle of the churn. It therefore follows 35 that by causing the shaft B to revolve, the movement of the shaft will be converted into a reciprocating motion, so that the lever C operates the churn.

E is a spur pinion keyed upon the shaft B. 40 F is a spur-wheel keyed to a shaft, G, which is journaled in the frame A. H is a spur pinion, also keyed to the shaft G, and arranged to gear with the spur-wheel I, so fastened to the shaft J that it will revolve freely 45 on it in one direction, but will carry the shaft with it if turned in the reverse direction. This shaft J is also journaled in the frame A, as indicated, and is designed to

carry the drum K, around which the rope or chain L is wound. On the end of the rope 50 or chain the weight N is attached. By turning the shaft J by means of a hand-crank, so as to wind the rope or chain L upon the drum K, the power of the descending weight will cause the shaft J to revolve, and through 55 its connection described with the shaft B the latter shaft will be driven. Although one weight and chain of wheels to connect to the shaft B would be sufficient for the purpose of driving the said shaft, we have shown in 60 the drawing two weights and a suitable set of wheels, as by them we are enabled to obtain greater power than could be secured by the use of a single weight.

In order to regulate the speed of the shaft 65 B, we provide a governor consisting of two balls, O, connected to a vertical spindle, P, journaled in the frame, as shown. This spindle has a pulley, Q, keyed to it, and connected by the belt R to the pulley S, keyed 70 or otherwise fastened to the shaft B. As this shaft revolves, a corresponding movement will therefore be given to the governor, which constitutes a check upon the speed of the said shaft. It will be seen that, as the governor 75 revolves, the balls, by flying out, produce a greater resistance, thereby checking the speed of the governor, and through it the speed of the shaft.

The weights O can be increased in heft; or 80 they may be so arranged on their arms that they may be adjusted up or down, it of course being clear that the farther away the balls are from the point where they connect with the spindle P the greater the resistance they 85 will present to the motion of the spindle.

What we claim as our invention is—

1. As an improved motor, the weight or weights N, connected by a chain or rope, L, adapted to be wound by hand upon a drum 90 or drums, K, which is or are connected by a chain of gear-wheels to the shaft B, in combination with the crank B', connected by the pitman D to the lever C, which is pivoted to the frame A, and arranged to impart a re- 95 ciprocating movement to a churn or other

machine, substantially as and for the purpose specified.

2. In a motor deriving its power from the descent of a weight or weights, the combination of a governor connected to the main shaft, driven by the descending weights in such a manner that the motion of the governor imparts a resisting power to this shaft in pro-

portion to the power consumed by the machine driven by the motor, substantially as and for the purpose specified.

LOUIS SEEBACH.
JOSEPH BETTSCHEN.
